UNITED STATES PATENT OFFICE.

WILLIAM H. BARKER, OF HARTFORD, CONNECTICUT, ASSIGNOR TO THE BEVIN BROTHERS MANUFACTURING COMPANY, OF EAST HAMPTON, CONNECTICUT.

BICYCLE-BELL.

SPECIFICATION forming part of Letters Patent No. 608,146, dated July 26, 1898.

Application filed May 3, 1898. Serial No. 679,567. (No model.)

To all whom it may concern:

Be it known that I, WILLIAM H. BARKER, a citizen of the United States, and a resident of Hartford, in the county of Hartford and State of Connecticut, have invented certain new and useful Improvements in Bells, of which the following is a full, clear, and exact description, whereby any one skilled in the art can make and use the same.

10 My invention relates more particularly to the class of bells used on vehicles for the purpose of sounding an alarm; and the object of my invention is to provide a bell of this class in which the striking mechanism may be brought into operative connection with a movable part for the purpose of sounding a bell.

20 To this end my invention consists in the device as a whole, in the combination of parts making up such a device, and in the details and their combination, as more particularly hereinafter described, and pointed out in the claims.

25 Referring to the drawings, Figure 1 is a view of a portion of the front fork of a bicycle, showing the front wheel with my improved bell operatively mounted in connection with the wheel on the fork. Fig. 2 is a detail view of the base-plate, looking inside, with the mechanism mounted thereon. Fig. 3 is a detail edge view of the bell with parts broken away to show construction. Fig. 4 is a detail view of a base-plate, showing a diagram of different positions of the pinion-lever.

30 35 In the accompanying drawings the letter *a* denotes the front fork of a bicycle, and *b* the front wheel mounted therein.

The letter *c* denotes a clamp secured to the front fork in any suitable manner and having 40 an arm *c'* connected therewith at one end, the other end of the arm bearing a base-plate *d* of a bell secured thereon in any suitable manner, a post *d'*, to which is secured a gong *d''*, forming a suitable means of connection between the base-plate and gong.

45 A hammer *e* is pivoted on the base-plate and is controlled in its striking movements by the springs *e'* *e''*, suitably mounted on the base-plate.

50 55 A striking-disk *f* is mounted on a post *f'*, secured to the base-plate, and a striking-gear

g is arranged to impart rotation to the striking-disk. A striking-pin *f''* is secured to the striking-disk in position to encounter a projection *e''* on the hammer *e* in the rotation of 55 the disk.

A striking-lever *h* is pivoted, preferably, to the base-plate on the outside, one end of the striking-lever being provided with a cord *h'* or like means for swinging the lever on its pivot. 60 To the opposite end of the lever is pivoted a shaft *i*, having mounted on one end a pinion *k* and on the other end a friction-disk *l*. This shaft *i* projects through a slot *d''* in the base-plate, the pinion *k* being located inside of the 65 base-plate. A spring *h''* holds the lever *h* at one limit of its play.

The pivotal point of connection of the striking-lever *h* is so located with reference to the striking-gear *g* that the pinion *k* as the lever is swung on its pivot shall swing past the gear and at a distance therefrom to cause the teeth of the pinion and gear to mesh. The path of movement of the pinion *k* in the swinging movement of the striking-lever as 70 the pinion engages the gear is in the same direction as that in which the gear rotates to operate the striking mechanism, and this insures the engagement of the teeth on the pinion and gear without liability of the teeth interfering with each other in a manner to wedge and prevent a proper operation of the device.

75 It is preferred that the lever shall swing in the same direction as that in which the pinion shall rotate to cause the proper sounding of the alarm.

I claim as my invention—

1. In a bell-striking mechanism including a gear, a swinging lever, a pinion mounted 90 on the lever, a friction-disk operatively connected with the pinion, means for rotating the friction-disk, and means for swinging the lever to cause engagement of the pinion and gear and friction-disk with driving means. 95

2. In a bell-striking mechanism including a gear, a swinging lever, a pinion mounted on the lever and adapted to be swung past a point at the periphery of the gear and on a radial line thereof with the teeth of the gear 100 and pinion engaging, a friction-disk connected with the pinion, means for rotating

the friction-disk, and means for swinging the lever to cause the pinion and gear and the friction-disk and driving means to engage.

3. In combination in a bell-striking mechanism including a gear, a swinging lever, a pinion mounted on the lever in position to engage the gear on a tangent to the pitch-line thereof, a friction-disk connected with the pinion, means for driving the friction-disk, and means for swinging the lever to cause the gear and pinion and the friction-disk and driving means to engage.

4. A support, a hammer mounted on the

support, a disk operatively mounted in connection with the hammer, a gong, a gear connected with the disk, a swinging lever, a pinion mounted on the lever, a friction-disk operatively connected with the pinion, means for driving the friction-disk, and means for swinging the lever to cause the pinion to engage the gear and the disk to engage the driving means.

WILLIAM H. BARKER.
